ATTORNEYS

UNITED STATES PATENT OFFICE.

WILLIAM ALBERT COLLVER, OF MARSHFIELD, OREGON.

MOVABLE CAP FOR SMOKESTACKS.

Application filed June 6, 1923. Serial No. 643,759.

To all whom it may concern:

Be it known that I, WILLIAM ALBERT COLLVER, a citizen of the United States of America, and a resident of Marshfield, in 5 the county of Coos and State of Oregon, have invented a new and Improved Movable Cap for Smokestacks, of which the following is a description.

My invention relates to a heater associated 10 with a fireplace. Pending concurrently with the present application is an application forming a division of an application filed by me April 21, 1922, Serial Number 555,861, and the subject matter of the present application is a modification of the devices claimed in the said pending divisional application. The said concurrently pending application was filed June 6, 1923, Serial Number 643,758.

20 The object of the present invention is to provide a novel valve means controlling the smokestack in question.

Reference is to be had to the accompanying drawings forming a part of this specification, it being understood that the drawings are merely illustrative of one example of the invention.

Figure 1 is an enlarged horizontal section through a chimney and smokestack in association with which my improved valve device is arranged, the section being taken in a plane indicated by the line 1—1, Figure 2, and looking in the direction of the arrows in said Figure 2;

35 Figure 2 is a vertical section as indicated by the line 2—2, Figure 1;

Figure 3 is a side elevation of the devices illustrated in Figures 1 and 2, part of the weighted ring being broken away.

40 In carrying out my invention in accordance with the illustrated example, the smokestack 136 has a fixed laterally extending plate 180 at the top of the chimney structure 163 through which the smoke from the smokestack may escape. Above the plate 180 is another plate or cap 181 which in the present example is vertically movable relatively to the plate 180 for which purpose said cap 181 is supported as at 100 on 45 a plurality of levers 184 disposed at the several sides of the chimney 163. The levers 184 are fulcrumed as at 185 between the ends thereof at the under side of said fixed plate 180.

Suspended from the levers 184 at the opposite end from the cap connections 100 is a weight ring 186 here shown as having link connections 101 with said levers. Said weight ring 186 has pockets 286 thereon at intervals adapted to receive sand, shot, or the like. The cap 181 at the under side may be strengthened by cross ribs 102. Thus, with an increase of draft the cap 181 functions automatically to open under an increased draft and lowers with a decrease of 55 the draft pressure.

For raising the cap 181 manually a rock shaft 103 is turnably supported in the chimney structure and has a lateral arm 104 to which a rope 105 is secured leading 60 to any point within convenient reach. The inner end of the shaft 103 has a lateral arm 106 terminating in a knob 107 disposed beneath the center of the cap 181 and adapted to engage said cap with the rocking of said shaft 103 by a pull on the rope 105. A weight 108 is provided on arm 106 to counterbalance the weight of the rope when the shaft 103 is at rest.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A structure of the class described including a smokestack, a cap over the smokestack and adapted to move vertically toward or from the top of the smokestack, and weighted levers fulcrumed between their ends, on which levers at an end of each said cap is mounted.

2. A structure of the class described including a smokestack, a cap over the smokestack and adapted to move vertically toward or from the top of the smokestack, levers fulcrumed between their ends, one end of each lever being secured to said cap, and a weight connected to the several levers at the opposite ends thereof.

3. A structure of the class described including a smokestack, a cap over the smokestack and adapted to move vertically toward or from the top of the smokestack, levers

fulcrumed between their ends, one end of each lever being secured to said cap, and a weight connected to the several levers at the opposite ends thereof; together with manually operable means for raising said cap, said means comprising a rock shaft having a member adapted to bear upwardly

against the cap when the shaft is rocked, a pull rope to rock said shaft for raising the cap, and a weight on said shaft tending to restore said rock shaft after movement by the pull rope. 10

WILLIAM ALBERT COLLVER.
